UNITED STATES PATENT OFFICE.

WILLIAM H. DRIGGS, OF WASHINGTON, DISTRICT OF COLUMBIA.

BAND-SEAT FOR PROJECTILES.

SPECIFICATION forming part of Letters Patent No. 469,631, dated February 23, 1892.

Application filed December 17, 1891. Serial No. 415,384. (No model.) Patented in England January 15, 1892, No. 837.

To all whom it may concern:

Be it known that I, WILLIAM H. DRIGGS, a citizen of the United States, residing at Washington, District of Columbia, have invented 5 certain new and useful Improvements in Band- Seats for Projectiles, (which I have patented in England, No. 837 of 1892, filed January 15, 1892;) and I do hereby declare the following to be a full, clear, and exact description of the invention, such as will enable others skilled in the art to which it appertains to make and use the same.

My invention relates to the manufacture of shells and projectiles, but more especially to 15 the process of banding the same, and has for its object to provide simple and efficient means for securing the band firmly in place.

The improvements consist in rolling, stamping, or pressing into the body of a projectile 20 a series of cross-lines or circles, into which the soft metal forming the band is forced by pressure, and of such other details of construction as will be hereinafter fully described, and specifically pointed out in the claim.

25 Reference is had to the accompanying drawings, wherein the same parts are indicated by the same letters.

Figure 1 represents a view of a shell or projectile having the grooves cut into the surface of the shell. Fig. 2 is a similar view of 30 a slightly-modified form in which the indentations are of circular form.

A designates a shell, having band-seat B formed in the surface thereof and extending 35 around its body in rear of the center. Within the band-seat B, I form a series of grooves or indentations b, crossing each other at angles and forming a "knurled" seat for the band C, as shown in Fig. 1. The band C is placed in 40 the seat so formed and subjected to pressure

sufficient to force the soft metal of the band into the interstices of the "knurling" of the seat and thus secure the band firmly in position.

In Fig. 2 I have shown the knurling formed 45 upon the surface of the shell, as at b', no groove being cut in the shell. In many instances this will be found sufficient and will obviate the necessity of forming a groove around the shell. 50

In Fig. 3 is shown a slightly-modified form, in which, in lieu of knurling the band-seat, I make the indentations in the form of circular slots, as shown at b⁴, the band C being forced into the said indentations by pressure, as in 55 the previous instance.

By knurling the band-seat and forcing the metal of the band into the interstices of the knurling under pressure, as hereinbefore described, I provide a simple means by which 60 the bands upon shells and projectiles may be secured firmly and rigidly in place.

Having thus described my invention, what I claim, and desire to secure by Letters Patent of the United States, is— 65

The combination, with a projectile having its rear portion cylindrical and having a number of grooves or depressions rolled or pressed upon a part of the exterior surface of said cylindrical portion of said projectile, of a band 70 of soft metal mounted over said grooves and compressed so as to fit partly in said grooves, substantially as and for the purposes described.

In testimony whereof I affix my signature in 75 presence of two witnesses.

WILLIAM H. DRIGGS.
